(57) CLAIM

The ornamental design for footwear, as shown and described.

DESCRIPTION

FIG. 1 is a front perspective view of footwear, showing my new design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a perspective view of an alternative embodiment thereof shown in FIG. 1;

FIG. 8 is a left side view thereof;

FIG. 9 is a right side view thereof;

FIG. 10 is a front view thereof;

FIG. 11 is a rear view thereof; and,

FIG. 12 is a top view thereof.

The broken line showing of a portion of the upper, sole, heel, heel cap, zipper, zipper pull, zipper track, buckle, buckle holes, and portion of the buckle strap is for illustrative purposes only and forms no part of the claimed design.
